UNITED STATES PATENT OFFICE

HERBERT S. HARDE, OF NEW YORK, N. Y.

INDEX OR DIRECTORY.

No. 858,340.

Specification of Letters Patent.

Patented June 25, 1907.

Application filed January 14, 1905. Serial No. 241,085.

To all whom it may concern:

Be it known that I, HERBERT S. HARDE, a citizen of the United States, residing in the borough of Manhattan, city, county, and State of New York, have invented new and useful Improvements in Indexes or Directories, of which the following is a specification.

This invention relates to indexes or directories for use in connection with telephones or for other purposes, and it has especial reference to the index of the kind disclosed in my co-pending application, Serial No. 237,492, filed December 19, 1904.

15 The object of the present invention is to provide an index or directory adapted to be rotatably mounted on any suitable support and presenting a plurality of leaves bearing names and addresses or other data, and so mounted upon the base of the device that each of the leaves may be shifted to bring the data written thereon into view without disturbing the other leaves.

25 Other minor objects of the invention and advantages thereof will be pointed out as the invention is hereinafter disclosed.

In the accompanying drawings forming part of this specification, I have illustrated two slightly different forms of embodiment 30 of the invention, and it is to be understood that other forms may be devised differing therefrom in details of construction but falling within the scope of the invention, which is clearly defined in the appended claims.

35 In the drawings, in which corresponding parts are designated by similar characters of reference, Figure 1 is a view in front elevation of one form of the invention. Fig. 2 is a view in transverse section through a directory or index in position upon a telephone transmitter, which is shown in elevation. Fig. 3 is a fragmentary elevational view of a slightly different form of the invention; and Fig. 4 is a fragmentary sectional view of the 45 form of the invention illustrated in Fig. 3.

Referring first to Figs. 1 and 2, 1 designates the base of the index or directory, which may be formed of any suitable sheet material having the required stiffness, and 50 which is preferably provided on its front face adjacent to the periphery with a stiffening ring or annulus 2, presenting a surface which is slightly inclined toward the center of the base which is circular in form and has 55 a central opening 3, which is sufficiently large to receive the mouthpiece 4 of a tele-

phone transmitter 5. Upon the base 1, I provide any suitable number of sector-shaped leaves 6, each of which is preferably provided with a plurality of index characters 7, which are disposed in different positions, so that they may be recognized when the leaf is in any position. The sector-shaped leaves 6 are arranged in a ring around the central opening of the base, so as to overlap, as best shown in Fig. 2, and each leaf is pivotally attached to the base at one of the corners adjacent to the center of the base. The attachment of each leaf to the base may be effected by means of an annular clip 8 of sheet metal or the like, which is directly secured to the base, as shown in Fig. 2, and has a flange 9 which overlies the base and receives the rivets 10 or other devices which serve as pivots for the leaves. The clip 8 serves not only as a support for the rivets 10 by which the leaves are secured, but it engages frictionally with the leaves when in normal position about the center of the base and so holds the leaves in the normal position. 80 The pressure exerted by the clip upon the several leaves is just sufficient to prevent the leaves from dropping out of normal position by their own weight, and when it is desired to shift one of the leaves to disclose more 85 fully the addresses or other data entered thereon, the leaf may be easily turned on its pivot by grasping the margin of the leaf between the thumb and the forefinger and drawing it in the direction indicated by the arrow in Fig. 1.

Referring to Figs. 3 and 4, 15 designates the base, which is a disk of sheet material similar to that above described and shown in Figs. 1 and 2. Upon this base a plurality of 95 sector-shaped leaves 16 are pivotally mounted so as to overlap when in normal position and closely surround the central opening 17 of the disk. The leaves 16 are pivoted adjacent to the periphery of the base by means of rivets 18 or other suitable fastening devices, which pass through corners of the leaves and permit them to be swung outward, as shown in Fig. 3. In this form of the invention, as in that already described, I preferably provide 100 an annular clip 19 adjacent to the center of the base and surrounding the central opening 19. This clip 19 has a flange 20 overlying the base and adapted to engage frictionally with the leaves 16 and hold them in normal 110 position.

Both forms of index already described and

illustrated in the drawings are adapted for use upon any suitable support and may occupy horizontal or vertical positions. They are designed primarily for mounting upon supports upon which they may be rotated to bring any leaf into position for convenient inspection, but it is obvious that they may be fixed upon walls, tables or the like, if desired, and the printing or lines upon the leaves may be so arranged as to bring the characters into proper position for reading when the leaves are turned out of their normal position.

While the invention is designed primarily for use as a telephone index or directory, any data to which frequent reference is necessary may be entered upon the leaves in lieu of the addresses and telephone numbers which are ordinarily kept thereon.

Having thus described my invention, what I claim as new and desire to secure by Letters Patent is:

1. An index or directory comprising a flat base, leaves independently pivoted on the base and arranged to overlap so that each leaf has when in normal position only a small portion exposed to view, and each leaf being susceptible of movement edgewise independently of all the other leaves so as to expose nearly the entire leaf.

2. An index or directory comprising a base, and a plurality of overlapping leaves pivotally mounted on the base, each leaf being susceptible of edgewise swinging movement independently of all the other leaves, and each leaf lying in direct contact with the base at the pivotal point.

3. An index or directory comprising a base and a plurality of leaves independently pivoted upon the base and arranged in such manner that each leaf when in normal position overlaps one immediately adjacent leaf

and is overlapped by the other immediately adjacent leaf.

4. In an index or directory, a base, and a plurality of leaves arranged in a ring on said base, said leaves being secured to the base by a series of separate pivots upon which the leaves are secured so as to swing edgewise, and each leaf being pivoted adjacent to one corner.

5. In an index or directory, a base, and a plurality of substantially sector shaped leaves arranged in a ring on said base and pivotally secured thereto so as to swing edgewise, each leaf being pivoted at a point adjacent to its outer margin.

6. In an index or directory, a base, a plurality of leaves radially arranged on the base and pivotally secured thereto, and an annular clip carried by the base and adapted to hold said leaves normally in overlapped position.

7. In an index or directory, a base having a central aperture, a plurality of overlapping leaves arranged around said aperture, and a plurality of pivots also arranged around said aperture upon which said leaves are mounted to swing edgewise.

8. An index or directory comprising a base, a plurality of overlapping leaves arranged around a point on said base, and a series of pivots for said leaves arranged substantially in a circle, said leaves when in normal position being radially arranged with reference to the circle in which the pivots are set and being symmetrically placed in relation to the center of said circle.

In testimony whereof, I affix my signature in the presence of two witnesses.

HERBERT S. HARDE.
